CLAIM

The ornamental design for a selfie stick, as shown and described.

DESCRIPTION

FIG. 1 is a front, right side, top perspective view of a selfie stick showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof; and,

FIG. 9 is a front, right side, top perspective view thereof when the legs of the selfie stick are disposed at their collapsed positions.

The broken lines depict portions of the selfie stick that form no part of the claimed design.

1 Claim, 9 Drawing Sheets
